UNITED STATES PATENT OFFICE

2,046,235

TOBACCO CAN

David Baden, Hazleton, Pa.

Application July 8, 1935, Serial No. 30,411

2 Claims. (Cl. 206—56)

This invention relates to a follower actuating and holding medium of the character set forth in my U. S. Letters Patent granted July 3, 1934 and numbered 1,964,718 and has for the primary 5 object the provision of a device of this character which will be simple in construction and cheap to manufacture and may be readily adapted to a tobacco can and the follower therein and protruding only a limited distance outwardly of the 10 can so that it may be easily manipulated to advance the follower as desired and will not in any way interfere with the carrying or handling of the can and further the device will hold the follower against lowering in the can when in any of 15 its adjusted positions.

With these and other objects in view, this invention consists in certain novel features of construction, combination and arrangement of parts to be hereinafter more fully described and 20 claimed.

For a complete understanding of my invention, reference is to be had to the following description and accompanying drawing, in which

Figure 1 is a vertical sectional view showing 25 my invention adapted to a tobacco can equipped with a follower.

Figure 2 is a horizontal sectional view through the can showing my invention resting upon the bottom of the can.

Figure 3 is a disrupted perspective view illustrating my invention.

Referring in detail to the drawing, the numeral 1 indicates a tobacco can wherein the tobacco 2 thereof is urged toward the mouth of the can 35 by a follower 3. To effect operation of the follower 3 my invention is employed which consists of a lever 4 constructed from a flat strip of metal having one end enlarged to form a follower engaging portion 5 disposed at a slight angle to the strip proper. The portion 5 contacts the follower, as shown in Figure 1. The lever 4 is 40 cut away to form a shank 6 and a finger piece 7. The shank 6 by being reduced in width over the width of the lever 4 defines to said lever shoulders 45 8 adapted to fulcrum on the bottom 9 of the can with the shank 6 projecting through a slot 10 in the bottom arranging the finger piece 7 exteriorly of the can. The lever 4 intermediate its ends is 50 cut away to form oppositely extending notches 11 defining between said notches a reduced portion 12.

A prop 13 has one end angularly disposed and notched, as shown at 14. The notch 14 has a restricted throat 15 opening outwardly through the 55 end of the prop. The notch 14 fits the notches 11 of the lever with the reduced portion 12 confined therein. The opposite end of the prop is

slightly beveled, as shown at 16, and rides upon notches 17 formed in the bottom of the can. Oppositely extending ears 18 are formed on the prop to contact opposite walls of the can for guiding the movement of the prop over the 5 notches on the bottom of the can.

In operation, to elevate or raise the follower 3, the finger piece 7 is grasped and swung in one direction causing the lever 4 to exert an upward pressure on the follower. During the upward 10 swinging movement of the lever, the prop ratchets over the teeth 17. The prop engaging any one of the teeth will retain the lever from a downward swinging movement, consequently maintaining the follower in any of its adjusted positions. 15

The prop may be readily assembled to the lever and the latter assembled to the can and also can be easily removed from the can when desired and detached from the prop should it be necessary.

Having described the invention, I claim:

1. In combination with a tobacco can having a follower and a slotted bottom wall provided with a series of teeth, a strip-like lever having one end enlarged and bent angularly and contacting the follower, said lever having its opposite end 25 notched and reduced to form shoulders to fulcrum on the bottom of the can and to provide a shank extendible through the slot of the bottom with a finger piece arranged exteriorly of the can, said lever having oppositely extending 30 notches forming therebetween a reduced portion, a strip-like brace having one end notched and provided with a restricted throat to said notch to receive the reduced portions between the notches of the lever, said brace having its 35 opposite end tapered for movement over the teeth.

2. In combination with a tobacco can having a follower and a slotted bottom wall provided with a series of teeth, a strip-like lever having one end 40 enlarged and bent angularly and contacting the follower, said lever having its opposite end notched and reduced to form shoulders to fulcrum on the bottom of the can and to provide a shank extendible through the slot of the bottom with a 45 finger piece arranged exteriorly of the can, said lever having oppositely extending notches forming therebetween a reduced portion, a strip-like brace having one end notched and provided with a restricted throat to said notch to receive the 50 reduced portions between the notches of the lever, said brace having its opposite end tapered for movement over the teeth, oppositely extending ears formed on the prop to contact opposite walls of the can to guide the movement of the brace 55 over the teeth.

DAVID BADEN.
